Primary Examiner — Kevin K Rudzinski

(57) **CLAIM**

The ornamental design for a hooded towel with ear-shaped pockets, as shown and described.

DESCRIPTION

FIG. 1 is a top-front-right perspective view of a hooded towel with ear shaped pockets showing my new design; FIG. 2 is an enlarged portion view taken from encircled portion labeled, “2” in FIG. 1;

FIG. 3 is a bottom-front-left perspective view thereof; FIG. 4 is a right-side elevational view thereof;

FIG. 5 is an enlarged portion view taken from encircled portion labeled, “5” in FIG. 4;

FIG. 6 is a left-side elevational view thereof;

FIG. 7 is a front elevational view thereof;

FIG. 8 is an enlarged portion view taken from encircled portion labeled, “8” in FIG. 7;

FIG. 9 is rear elevational view thereof;

FIG. 10 is a top plan view thereof;

FIG. 11 is a bottom plan view thereof;

FIG. 12 is a front elevational view, wherein the ear pockets are lifted to reveal a fastener underneath; and,

FIG. 13 is an enlarged portion view taken from encircled portion labeled “13” in FIG. 12.

The broken lines showing a fastener is included for the purpose of illustrating environmental structure and forms no part of the claimed design.

1 Claim, 13 Drawing Sheets
